DRAIN FOR SINKS.

1,224,603.

Specification of Letters Patent.

Patented May 1, 1917.

Application filed February 10, 1914, Serial No. 817,916. Renewed September 2, 1916. Serial No. 118,312.

To all whom it may concern:

Be it known that I, ROBERT CLARK, a citizen of the United States, residing at Bridgeport, in the county of Fairfield and State of Connecticut, have invented certain new and useful Improvements in Drains for Sinks, of which the following is a full, clear, and exact description.

This invention relates to a drain or waste fixture, especially applicable to kitchen sinks, but certain features of my improvements are not limited to this particular application.

The primary object of the invention is to provide a drain fixture in which the strainer may be very readily inserted into and removed from the outlet bushing or shell in the sink bottom, and wherein an ordinary stopper of rubber, metal, or the like, may be readily substituted for the strainer when it is desired to fill the sink with water. It is also proposed to furnish a fixture of the type indicated in which the strainer, or the stopper or plug may be seated in the same seat in the bushing and firmly held therein to serve its intended purpose.

To these and other ends, the invention consists in the novel features and combinations of parts to be hereinafter described and claimed.

In the accompanying drawing,

Figure 1 is a top plan view of a drain fixture embodying my improvements, showing the strainer in place in the outlet shell or bushing.

Fig. 2 is a similar view, showing the stopper or plug in its seated position.

Fig. 3 is a side elevation of the bushing, and the means connecting it with the waste pipe.

Fig. 4 is a section on line 4—4 of Fig. 1, with the waste pipe omitted.

Fig. 5 is a section on line 5—5 of Fig. 2.

Fig. 6 is a detail edge view of the strainer detached; and

Fig. 7 is a bottom view of the strainer detached.

Referring to the drawing, 10 is an outlet bushing or shell, adapted to be secured in the usual manner in an opening in the bottom of the sink, having the usual substantially horizontal annular flange 11 adapted to overlie the bottom wall of the sink around the opening formed in the latter. A nut 55 (not shown) engaging the screw threads 12

on the exterior of the bushing is adapted to clamp the bushing in place, and the lower end of the bushing has secured thereto in a suitable manner the customary waste pipe 13, as shown in Fig. 5. At the upper end or mouth of the bushing, the latter is provided with a smooth beveled inner surface 14, the lower margin or boundary of which projects out slightly into the open interior part of the bushing in such a manner as to present a shoulder 15. In other words, the lower edge of the beveled seat in the inlet mouth of the bushing is of less diameter than the interior diameter of that portion of the bushing wall which is immediately below the seat. This provides a locking shoulder for suitable securing lugs 16 of a strainer 17, adapted to be seated and held in the mouth of the bushing in the manner shown in Fig. 4.

The strainer 17 is preferably formed of a perforated sheet metal disk, and the lugs 16 are preferably formed integral with the strainer disk by bending down radial extensions projecting integrally from the strainer blank. The lugs 16 are preferably curved, as shown, and the strainer is so fitted relatively to the seat 14 of the bushing that as the strainer is forced downward into the bushing, the lugs 16 in sliding down over the beveled surface of the seat will be forced inward until their lower ends in passing below and beyond the shoulder 15 move outward as the result of the spring in the metal, and thereby lock the strainer firmly in its seat. When it is desired to remove the strainer, this can be readily effected by inserting a knife, or other instrument, into the space between the strainer and the seat 14, so as to pry the strainer out of the bushing.

When the strainer has been removed an ordinary stopper or plug 18 having a beveled side wall may be seated in the beveled seat 14 in the customary manner, as shown in Figs. 2 and 5, so that the sink may be filled with water. The substitution of the strainer for the stopper and vice versa can be effected very quickly and easily, and the fixture is very simple, efficient and inexpensive.

By preference, the bushing 10 will be made of sheet metal so that its bulk and cost will be reduced as compared to a cast metal bushing. In this case, the seat 14 will be formed by indentation of the side wall of

the tubular sheet metal blank, which may be produced, for example, by spinning a groove 19 in said wall at the outside, which groove is so formed as to project the metal inwardly at the inner surface of the blank 5 to form a beveled seat of proper shape. The shoulder 15 for locking the strainer in position is, in this case, formed as a necessary incident to the creation of the beveled seat. This is a feature of some importance in 10 producing a fixture of minimum cost.

It will be seen from the foregoing that in the preferred form of my invention which I have selected for illustration, the bushing is 15 provided with a substantially horizontal laterally projecting flange at the upper end thereof, adapted to overlie the bottom wall of the sink around the opening in the latter, said bushing being provided at the upper end or mouth thereof with a smooth, substantially upright seat 14 beveled to make water tight contact substantially throughout its area with an ordinary plug or stopper having a beveled side wall, the diameter of 20 the bushing being enlarged immediately below the beveled stopper seat to form a shoulder 15 for locking the strainer in place. It will be seen also that the strainer disk is of a diameter substantially equal to the diameter of the upper portion of the stopper seat, and that it is supported in said seat substantially flush with the horizontal flange 11 by means of spring lugs depending from the periphery thereof, and adapted to engage 25 the beveled wall of the stopper seat so as to spring said lugs inwardly as the strainer is inserted into the seat, and permit said lugs to spring outward again into locking engagement with the shoulder 15, as said lugs 30 pass below the stopper seat. The spring lugs are of such length that when their lower ends are in locking engagement with the shoulder 15, the strainer disk to which they are attached is supported in the upper end 35 of the stopper seat, as stated.

It will be seen that in the embodiment shown, the flange on the upper end of the bushing is constructed and adapted to overlie the bottom wall of the sink with a wide 40 contacting surface, so that the joint between the bushing and the sink, basin or tub can be readily made water-tight, and that the bushing has a wide smooth seat adapted to make a good water-tight contact with an ordinary plug or stopper. The plug and seat 45 are usually slightly tapered, as shown, but this is not always essential.

What I claim is:

1. In a drain fixture for sinks and the like, the combination of a bushing adapted 50 to extend through an opening in the bottom of the sink and having exterior screw threads for a nut adapted to clamp the bushing in place in the sink bottom, a lateral 55 flange projecting horizontally from the

upper end of said bushing to overlie the bottom wall of the sink around the opening in said wall, said bushing having a smooth, substantially upright seat at the upper end or mouth thereof to make water tight contact substantially throughout its area with an ordinary plug or stopper having a slightly beveled seating surface, a strainer disk of a diameter substantially equal to the diameter of the mouth of the bushing, and 70 means for detachably engaging said strainer disk with a part of the bushing below said stopper seat to secure the strainer detachably in said seat when the stopper is removed, with the strainer substantially flush 75 with said horizontal flange; substantially as described.

2. In a drain fixture, the combination of a bushing having an integral outwardly directed flange projecting laterally from the upper end thereof, said flange constructed and arranged to overlie the bottom wall of the sink with a wide contacting surface, said bushing having a wide smooth seat adapted to make water-tight contact with an ordinary tapered plug or stopper, a strainer disk adapted to be inserted into said bushing sufficiently far to make its top substantially flush with the top of the bushing, and means carried by said strainer disk for engaging 90 the bushing wall to prevent accidental displacement of said strainer disk with respect to the bushing, substantially as described.

3. In a drain fixture for sinks and the like, the combination of a bushing, a substantially horizontal laterally projecting flange on the upper end of the bushing adapted to overlie the bottom wall of the sink around the opening in the latter, said bushing being provided at the upper end or mouth thereof 100 with a smooth, substantially upright seat for an ordinary stopper or plug having a beveled seating surface, a shoulder on the wall of the bushing beneath said seat, a flat strainer disk of a diameter substantially 105 equal to the maximum diameter of the stopper seat, and lugs on said strainer disk formed by bending downward radial tongues extending beyond the periphery of said disk, said lugs being adapted to engage said 110 shoulder below said stopper seat to hold the strainer disk in said stopper seat substantially flush with said horizontal flange; substantially 115 as described.

4. In a drain fixture for sinks and the like, the combination of a sheet metal bushing having a substantially horizontal laterally projecting flange on the upper end thereof, the outer surface of said bushing being provided with screw threads for engagement with a nut to clamp the bushing in the bottom wall of the sink, said bushing having a portion spun therein immediately below said horizontal flange to present a smooth, substantially upright seat adapted 120

- to make water tight contact throughout substantially its entire area with an ordinary plug or stopper having a beveled seating surface, said bushing being of enlarged diameter immediately below said stopper seat so as to provide a shoulder, a flat strainer disk of a diameter substantially equal to the diameter of the upper portion of said stopper seat, and lugs on the peripheral portion 10 of said strainer disk adapted to engage and interlock with said shoulder, said lugs being of such length as to support said strainer disk in the upper portion of the stopper seat substantially flush with said horizontal 15 flange; substantially as described.
5. In a drain fixture, the combination of a bushing having an integral outwardly directed flange projecting laterally from the upper end thereof, and having a wide contacting surface on the sink bottom around the opening in the latter, said bushing having a tapered wide smooth seat formed directly in the wall thereof at the mouth of the bushing, adapted to make water-tight 20 contact with an ordinary tapered plug or stopper, a flat strainer of thin metal, of substantially the same diameter as the upper part of said stopper seat, adapted to fit in the upper part of said seat, substantially 25 flush with said outwardly directed flange, and means carried by said strainer for engaging the bushing wall and detachably holding said strainer in the aforesaid flush position, substantially as described.
- 30 6. In a drain fixture, the combination of a bushing adapted to extend through an opening in the bottom of the sink and having exterior screw threads for a nut adapted to clamp the bushing in place in the sink bottom, a flange projecting laterally from the upper end of said bushing having a wide contacting surface for the sink bottom, and a wide smooth, substantially upright seat formed directly in the wall of the bushing at the mouth thereof, and adapted to make water-tight contact with an ordinary tapered 35 plug or stopper, a strainer disk of a diameter substantially equal to the diameter of the upper portion of the stopper seat, adapted to be inserted into said seat sufficiently far to make its top flush with the top of the bushing, and means carried by said strainer disk for engaging the bushing wall to prevent displacement of the strainer disk with 40 respect to the bushing, substantially as described.
- 55 7. In a drain fixture, the combination of a bushing having an integral outwardly directed flange projecting laterally from the upper end thereof to overlie the sink bottom over a relatively wide surface, and a wide smooth, substantially upright seat adapted to make water-tight contact with an ordinary tapered plug or stopper, said bushing having exterior screw threads for a nut to clamp the bushing in place in the sink bottom, a substantially flat strainer disk adapted to be inserted into said bushing sufficiently far to make its top substantially flush with said flange, said strainer disk having a plurality of depending lugs adjacent the periphery thereof, and a shoulder in the bushing wall at the lower margin of said wide smooth stopper seat, coöperating with said lugs to hold the strainer disk detachably in the aforesaid substantially flush position, substantially as described.
8. In a drain fixture for sinks and the like, the combination of a bushing having an integral outwardly directed flange projecting from the upper end thereof, to form a wide contacting surface with the sink bottom, said bushing having exterior screw threads for a nut to clamp the bushing in place in the sink bottom and also provided with a wide smooth seat formed directly in the wall thereof at the mouth of the bushing, adapted to make water-tight contact with an ordinary tapered plug or stopper, a flat strainer disk of perforated sheet metal 90 adapted to be inserted into said bushing sufficiently far to make its upper surface substantially flush with the upper surface of said laterally projecting flange, said bushing having a shoulder located at the lower margin of said wide smooth stopper seat, and said strainer disk being of substantially the same diameter as the upper portion of said stopper seat, and lugs depending from the periphery of said strainer disk and co-operating with said shoulder to support said disk detachably in the upper portion of said stopper seat, substantially flush with said laterally projecting flange, substantially as described.
- 100 105 In witness whereof, I have hereunto set my hand on the 6th day of February, 1914.

ROBERT CLARK.
